UNITED STATES PATENT OFFICE.

ROBERT KEPNER, OF POTTSTOWN, PENNSYLVANIA.

TAG.

No. 916,716.

Specification of Letters Patent.

Patented March 30, 1909.

Application filed March 10, 1908. Serial No. 420,224.

To all whom it may concern:

Be it known that I, ROBERT KEPNER, a citizen of the United States of America, residing at Pottstown, in the county of Montgomery and State of Pennsylvania, have invented new and useful Improvements in Tags, of which the following is a specification.

This invention relates to tags, the main object of the same being to provide a simple, inexpensive and effective tag which may be instantly applied to any desired article and which, by reason of the special construction hereinafter described, is adapted to clench itself in position on the article to which it is applied, a double clenching action being effected.

With the above and other objects in view, the nature of which will more fully appear as the description proceeds, the invention consists in the novel construction, combination and arrangement hereinafter fully described, illustrated and claimed.

In the accompanying drawing.—Figure 1 is a plan view of the tag before bending the same. Fig. 2 is an edge view thereof after the prongs have been bent to one side of the body. Fig. 3 is a detail section showing the manner of applying the tag to the article. Fig. 4 shows the tag after the operation of applying the same to an article has been completed. Fig. 5 is a detail section illustrating more in detail the coöperation of the parts of the tag when pressure is applied thereto to clench the same in its final position. Fig. 6 is an edge view of the tag partly folded.

The tag is stamped out of soft sheet metal, or in other words, sheet metal which is soft enough to admit of the bending and clenching action hereinafter fully described. The blank from which the tag is subsequently bent into shape is all in one piece, and in the preferred embodiment of the invention, the body 1 of the tag is oblong and is reduced in width centrally to form a relatively narrow neck 2 along which the tag as a whole is folded in applying the same to any article.

By reducing the body of the tag centrally, the tag is caused to comprise relatively wide end portions 3 and 4, and in stamping out the blank, a pointed prong 5 is left projecting from one end of the blank, while another prong 6 is punched out of the body of the blank adjacent to the opposite end of the body, but sufficiently removed therefrom to

leave ample space for the clenching or bending of the other prong 5 when the tag is folded about the margin or edge of the article to which it is subsequently applied.

In applying the tag to any article, the tag is folded along the reduced center, and the end portions thereof are carried to opposite sides of the article which, in Fig. 3, is illustrated at 7 and shown in the form of a single ply or thickness, while in Figs. 4 and 5 such article or body is indicated as composed of a number of plies or thicknesses which are thus bound together by the tag which thereby also acts as a clip. When pressure is brought to bear upon the oppositely lying portions of the tag the prongs 5 and 6 are forced through the article in the manner indicated in Figs. 3, 4 and 5, until the points of the prongs come in contact with the body of the tag at opposite sides of such article, whereupon further pressure applied to the opposite portions of the tag results in deflecting the points of the prongs against the metal body of the tag, resulting in clenching the ends of the prongs on opposite sides of the article to which the tag is applied. This forms a double clench or lock which effectually prevents the escape and loss of the tag.

The tag may be formed of any such soft metal, as aluminum, brass, copper or German silver and is all in one piece. Either or both end portions of the tag may have represented thereon in any desired manner such designs as monograms, insignia, private marks or symbols, and in fact the tag may be used for a great variety of purposes, such as a laundry marker or clothes identifying device and may also be used for the purpose of applying trade - marks to various articles, also for binding a number of sheets of paper or other material together.

It is practically impossible to remove the tag from the article without destroying it, so impairing its utility as to prevent the subsequent use thereof.

Having thus described the invention, what is claimed as new, is:—

A soft sheet metal tag comprising an oblong body, and prongs located at unequal distances from the center of the body, one prong projecting from one extreme edge of the body, and another prong being punched from the body within the margin of the opposite extremity thereof, the said prongs being bent

substantially at right angles to the body and being located so as to slide in contact with one another when the end portions of the body are folded and pressed toward each other and cause the points of the prongs to be deflected against the body in reverse directions.

In testimony whereof I affix my signature in presence of two witnesses.

ROBERT KEPNER.
